(57) **CLAIM**

The ornamental design for a days of the week hanging sign set, as shown and described.

DESCRIPTION

FIG. 1 is a front elevational view of a days of the week hanging sign set showing my new design;
FIG. 2 is a rear elevational view thereof;
FIG. 3 is a side view taken from the left side of FIG. 1, the right side view being a mirror image thereof;
FIG. 4 is a top plan view; the bottom plan view being a mirror image thereof; and,
FIG. 5 is a perspective view of a single sign of the set in use. The broken line showing a clothes hanger in FIG. 5 is for illustrative purposes only and forms no part of the claimed design.
